UNITED STATES PATENT OFFICE.

LEVI S. GARDNER, OF SHREVEPORT, LOUISIANA.

VISIBLE CARBURETER.

1,146,150.

Specification of Letters Patent. Patented July 13, 1915.

Application filed November 1, 1912. Serial No. 729,071.

To all whom it may concern:

Be it known that I, LEVI S. GARDNER, a citizen of the United States, residing at Shreveport, parish of Caddo, State of Louisiana, have invented a certain new and useful Improvement in Visible Carbureters, and declare the following to be a full, clear, and exact description of the same, such as will enable others skilled in the art to which it pertains to make and use the same, reference being had to the accompanying drawings, which form a part of this specification.

One of the primary objects of my invention is to produce a carbureter the operation of which may be observed from without. In other words, I desire to produce what may be called a "visible" carbureter.

An object of my invention subsidiary to this main object is to produce controlling and adjusting means for a visible carbureter which will permit the carbureter to be adjusted and regulated at will while it is in operation and without disarranging any of its parts.

Another object of my invention, subsidiary to the foregoing primary object, is so to construct a visible carbureter that its workings may be exposed to view in a simple and compact structure which may be placed on the dash board of an automobile facing the driver or in a similar position on some wall, cover or partition adjacent to an engine, while the parts of the carbureter which it is desired to keep warm may be concealed behind the dash board or other member and lie in proximity to the engine which it supplies.

A further primary object of my invention is to produce a simple and novel carbureter which will automatically adjust itself to respond to the varying service conditions encountered.

The various features of novelty whereby my invention is characterized will hereinafter be pointed out with particularity in the claims; but for a full understanding of my invention and of its objects and advantages, reference may be had to the following detailed description taken in connection with the accompanying drawings, wherein:

Figure 1 is a front view of a carbureter arranged in accordance with a preferred form of my invention; Fig. 2 is a transverse section through the carbureting device or member of the carbureter; Fig. 3 is a section on line 3—3 of Fig. 2; Fig. 4 is a section on line 4—4 of Fig. 3; Fig. 5 is a section on line

5—5 of Fig. 3; and Fig. 6 is a side elevation of the carbureter, the float chamber being shown in section.

In order to make the operation or action of the carbureter visible, I provide the carbureting chamber with transparent walls through which the stream of gasoline or other combustible issuing from the nozzle and the mingling of this stream with the incoming air may be observed. I also provide a suitable transparent gage arranged in proximity to the carbureting chamber for showing the height of the gasoline or other combustible in the float chamber or other reservoir; the other elements of the carbureter being so disposed that they will not interfere with the convenient inspection of the action of the carbureter and of the liquid level from some convenient point, such as from the seat of an automobile, motor boat or aeroplane. In order to secure automatic control which will make the carbureter adjust itself to respond to the load on it, I prefer to make the carbureting device of a series of individual units arranged in multiple and some or all of the units containing automatic governing means. The incoming air and the carbureted air may be controlled by any usual throttle valves common to all of the units; but I prefer to provide separate manual means for controlling the flow of gasoline or combustible into each one of the carbureting chambers. This arrangement of individual manual regulation of the flow of combustible permits each unit to be regulated accurately while the carbureter is in use and its action capable of being watched; thus permitting the initial adjustments to be effected while the carbureter is being observed under actual service conditions. With the initial adjustments properly made, the automatic controllers or governors will thereafter produce automatic regulation to increase or decrease the number of carbureting units in action according to the demand upon the carbureter. These various features of my invention may of course be embodied in many different forms but, for the sake of clearness and brevity, I have illustrated and shall describe in detail only a single embodiment.

Referring to the drawings, 1 represents an air conduit through which is drawn the air used by the carbureter and 2 is the conduit out of which the carbureted air passes to the engine for consumption; the members

1 and 2 being therefore respectively the inlet and the outlet for the carbureter. If desired, the conduits 1 and 2 may be surrounded by a suitable jacket, 3, within which a suitable heating medium may be placed in order to keep the two conduits warm. These two conduits, with their jacket, may be formed in any suitable way, preferably by being cast in a single piece with the outlet conduit lying above the inlet conduit. At the front ends of the conduits is formed a plate or flange, 4, which is preferably large enough in its transverse dimensions to conceal behind it the remainder of the casting. The two conduits extend forwardly beyond the plate and there terminate in manifolds, 5 and 6, arranged one below the other. The manifolds lie parallel with each other and are extended laterally for any desired distance depending upon the number of individual carbureting chambers which it may be desired to have. In the particular arrangement illustrated, there are five carbureting chambers and these are produced by connecting the two manifolds together with transparent tubes, 7 to 11, inclusive. Each tube rests at its lower end in a suitable packed seat, 12, surrounding an outlet port, 13, arranged in the top of the manifold, 5. Each tube extends at its upper end into an opening, 14, in the bottom wall of the upper manifold, 6, but does not project upwardly through this opening into the chamber within the manifold. Around each of the openings, 14, within the upper manifold, is a seat, 15, upon which rests a cup-shaped shell as indicated at 16 to 20, inclusive. Between the bottom of each of the cup-shaped members and the top of the adjacent tube is a suitable packing ring, 21. In the top wall of the upper manifold, directly above each of the openings, 14, is a series of openings, 22, into which are screw threaded caps or plugs, 23, these caps or plugs engaging with the upper edges of the cup-shaped shells and pressing them firmly down against their seats. By properly proportioning the packing rings, 21, the seating of the cup-shaped shells causes the packing rings both at the top and at the bottom of the transparent tubes to be compressed so as to produce tight joints. The walls of the cup-shaped shells, 16 to 20, are made in skeleton form and the bottoms are cut away so as to leave only narrow annular flanges around the sides. Thus the cup-shaped shells offer no obstruction to the upward flow of fluids out of the tubes and into the main chamber of the upper manifold. I employ the cup-shaped shells not only for the purpose of holding the transparent tubes in place but also to form part of automatic controllers or governors for the individual carbureting chambers. To this end I place in each of the cup-shaped shells, ex-

cept the first, a ball which co-operates with the annular flange at the bottom to form a valve adapted to open and close communication between the upper manifold and the corresponding carbureting chamber. The 70 balls constantly tend to drop into their seats and they do seat themselves whenever the suction in the upper manifold is not great enough to raise them; the lifting of one of the balls, and the cutting in of the corresponding carbureting chamber depending therefore upon the suction of the engine on the discharge side of the carbureter. Consequently, by varying the proportion between the weight of the ball and the area of 75 the port which it closes throughout the series, one ball after another can be caused to rise as the suction on the carbureter increases, thus bringing into play one unit after another as the demand increases. In 80 the same way, whenever the demand decreases, the balls will drop one after another in the reverse order in which they rose, thus automatically cutting down the capacity of the carbureter to suit the demand. 90

Each carbureting chamber is supplied with gasoline or other combustible through an individual nozzle, 30, these nozzles projecting up through the lower manifold to points within the transparent tubes. For 95 convenience, there may be formed on the under side of the lower manifold a conduit, 31, which serves as a third manifold to supply the liquid fuel to the nozzles. The effective opening through each of the nozzles 100 is controlled by means of a suitable manual valve, 32, these valves being preferably needle valves so that a fine adjustment may be obtained. The liquid combustible may be supplied to the manifold 31 in any suitable 105 way. In the arrangement shown, I have located a float chamber, 35, behind the plate 4 and at one side of the inlet and outlet conduits 1 and 2; the float chamber being supported by means of a pipe, 36, attached to 110 a nipple, 37, on the rear side of the plate. On the front of the plate is a short section of pipe, 38, which leads from the nipple to the manifold 31. Projecting upwardly from the pipe 38 is a small transparent stand-pipe, 39, closed at the top by means of a cap provided with a perforation, 40. The member 39 lies just behind and between the first two carbureting tubes so as to be visible from the front. The height of the liquid 115 combustible in the nozzles and in the source of supply is shown by the stand-pipe, the liquid level in the stand-pipe being the same as in the supply reservoir and in the nozzles. Furthermore as the liquid combustible flows 120 to the manifold 31, any air bubbles in it are separated therefrom, rise up through the liquid in the stand-pipe and escape to atmosphere so that the nozzles are supplied with a liquid free from air. 125 130

It will be seen that the float chamber is supplied with combustible through a nipple, 42, opening into the bottom thereof, a branch passage, 43, leading from the nipple 42 to the pipe 36 which carries the liquid to the carbureting devices. Within the float chamber is a valve having an elongated vertical stem, 44, projecting out through the top of the chamber; the valve 45 at the lower end of the stem being adapted to coöperate with the seat just below the passage 43 so that the passages leading to the float chamber and to the carbureting devices are opened and closed together. In the float chamber is a float, 46, loosely surrounding the valve stem. Screw-threaded through the top of the float chamber is a member 47 on the inner end of which are pivotally mounted two arms, 48. One end of each of the arms is connected to the valve stem by a suitable ball and socket joint, 49, or in any other suitable way. The outer ends of the two arms are counter-weighted, as indicated at 50, so that, when free to do so, the counter-weighted ends of the arms drop down and cause the valve to be lifted from its seat. The counter-weighted ends of the arms are adapted to be engaged by the top of the float, as the float rises to a predetermined level, causing the counter-weighted ends of the arms to be lifted and the opposite ends to be lowered and thereby seat the valve and shut off the flow of combustible into the float chamber. When the valve is up, the combustible flows directly from the source of supply to the carbureting devices, without passing through the float chamber, the float chamber serving simply as a regulator. When the valve is closed, however, the carbureting devices draw their supply of combustible from the float chamber and thus allow the float to descend and open the valve again. It will be seen that by turning the member 47 in one direction, all the parts carried thereby will be raised so that the float must rise higher before it will close the valve than it did before the member 47 was turned. In the same way, by turning the member 47 in the opposite direction, the parts carried thereby will be lowered so that the valve will be seated before the float has risen as high as was necessary in the original position of the member 47. In other words, by simply turning the member 47 in one direction or the other, the liquid level in the system, including the nozzles, may be varied at will and adjusted to a nicety.

It will be seen that the tubes 7 to 11, inclusive, are illustrated as increasing in size progressively from the first to the last, the ball valves 24 to 27 increasing in a similar order. I prefer this arrangement because when an engine starts up, it requires a rich mixture which, because a high speed has not yet been attained, will be furnished by

the smallest carbureting chamber. As the speed of the engine increases, the mixture should preferably be less rich and, if the nozzle in the second tube is the same as the nozzle in the first, the larger diameter of the second tube, when the automatic valve is lifted, causes the air flowing up through this tube to have a smaller percentage of combustible than that flowing through the first tube. In the same way, as each tube is cut in, it supplies a somewhat weaker mixture than those which preceded it, so that the best mixture is automatically obtained at all speeds. Furthermore, by making the first tube of the series quite small, it will be working at full capacity at a very low speed of the engine and therefore the first carbureting unit of the series may be adjusted with accuracy, something which would be impossible if the tube were larger.

When the carbureter is first put into use, the engine is run at a low speed until the valve, 32, of the first unit can be adjusted to give just the desired mixture for this speed. The speed of the engine is then increased until the automatic valve in the second unit is lifted, and then the manual valve of the second unit is carefully adjusted until the best results are obtained from two units at this speed. In this same way, the speed of the engine is increased gradually until all of the units have been brought into play, each unit being adjusted independently of the others as it is brought into action. After the adjustment has once been made, assuming that the quality of the combustible and the character of the atmosphere do not change, the carbureter will automatically adapt itself at all times to supply the proper mixture best for the particular speed at any given instant. When the quality of the combustible changes it is usually sufficient to adjust only the first carbureting unit of the series, the manual valve being opened more widely or closed to a greater extent depending upon the character of the combustible.

It will be seen that there are no parts of the carbureter which obstruct a view of the transparent carbureting chambers or of the stand-pipe which shows the level of the liquid in the system, when the carbureter is held so that the carbureting devices are in front.

In mounting the carbureter on an automobile, an opening may be cut through the dash so as to permit the inlet and outlet conduits and all parts behind the flange or plate 4 to lie under the hood and out of sight, the plate or flange acting as a cover for the opening. Consequently there is exposed on the dash only a compact series of carbureting tubes and the level indicating tube, these being all the parts which the driver needs to see in order to know the condition of the fuel supply and the manner in which the

engine is being fed. The inlet and outlet conduits, being under the hood, are in a warm atmosphere and furthermore, the air which is drawn into the carbureter is clean, 5 warm air taken directly from the interior of the hood and therefore free from dust and dirt. In motor boats, aeroplanes and elsewhere, the carbureter may likewise be mounted in such a position that only the carbureting 10 devices are exposed while the rest of the carbureter may lie in the warm atmosphere next to the engine. It will also be seen that, in addition to the advantages already pointed out, my improved carbureter has the 15 advantage of simplicity of construction and of accessibility to the working parts. The openings in the walls of the upper manifold are so proportioned that the cup-like shells and the carbureting tubes may be lifted out 20 through the top of the upper manifold upon unscrewing the several caps or plugs. This permits the tubes to be removed and cleaned or replaced readily, and gives convenient access to the nozzles.

25 While I have illustrated and described with particularity only a single preferred form of my invention, I do not desire to be limited to the exact structural details thus illustrated and described; but intend to 30 cover all forms and arrangements which fall within the terms employed in the definitions of my invention constituting the appended claims.

I claim:

35 1. In a carbureter, a supporting plate, a carbureting unit on one side of the plate, a float chamber on the opposite side of the plate, a connection between said float chamber and the carbureting unit, and conduits 40 extending through said plate to conduct air to and carbureted air away from the carbureting unit.

2. In a carbureter, a supporting plate, a carbureting unit on one side of the plate, a 45 fuel supplying means on the opposite side of the plate, a connection between said fuel supplying means and the said unit, and conduits extending through said plate to conduct air to and carbureted air away from the said unit, said unit having a transparent wall.

3. In a carbureter, a supporting plate, a carbureting unit located in front of the plate and including a chamber having transparent 55 walls, means located behind said plate for delivering the carbureting element into the aforesaid chamber, an air conduit lying behind said plate and communicating with said chamber, and a conduit for the carbureted air lying behind said plate and having its front end connected to said chamber.

4. In a carbureter, a supporting plate, two separated manifolds on the front side of the plate, a series of transparent tubes extending between and connecting said mani-

folds, an air supply conduit lying behind said plate and connected to one of said manifolds, a conduit for carbureted air lying behind said plate and connected to the other of the aforesaid manifolds, a third manifold 70 lying in front of said plate, means behind the plate for supplying the carbureting element to said third manifold, and a delivery nozzle leading from the third manifold to each of said transparent tubes. 75

5. In a carbureter, a supporting plate, a carbureting device including a series of transparent tubes arranged side by side in a row in front of the plate, means behind said plate for supplying air and a carbureting 80 element to said tubes, and a conduit for carbureted air lying behind and extending through said plate away from said carbureting device.

6. In a carbureter, a supporting plate, a carbureting unit on one side of the plate, means for supplying a carbureting element to said unit, and conduits extending through said plate to conduct air to the said unit and carry away the carbureted air therefrom, 90 said unit having a carbureting chamber provided with a transparent wall.

7. In a carbureter, a series of carbureting chambers, means for delivering air and a carbureting element into corresponding ends 95 of said chambers, an outlet conduit connected to the opposite ends of the chambers for carrying away the carbureted air, and valve devices in the outlet ends of a portion only of said chambers for controlling the 100 flow therethrough, said valve devices being under the control of the suction in said conduit and being so constructed and arranged that the valves are opened successively during an increase in the suction beyond a pre- 105 determined minimum.

8. In a carbureter, two separated manifolds, one of said manifolds having a series of ports surrounded by seats in the side directed toward the other manifold, the other 110 manifold having openings extending entirely therethrough and registering with said ports, carbureting tubes extending through said openings and resting at one end in said seats, and means engaging with 115 the opposite ends of the tubes and with the adjacent manifold for holding the tubes in place.

9. In a carbureter, an air chamber having in one side a port surrounded by a seat, a 120 second chamber spaced apart from the first chamber and having openings extending through two opposed walls in registration with said port, a tube extending through one of said openings and resting at one end 125 in said seat, and a detachable part closing the other of said openings and holding said tube on said seat.

10. In a carbureter, an air chamber having in one side a port surrounded by a seat, 130

second chamber spaced apart from the first chamber and having openings extending through two opposed walls in registration with said port, a tube extending through one of said openings and resting at one end in said seat, a combined valve seat and valve retainer resting upon the end of the tube in said second chamber, and a cap screwed into the second of said openings and engaging said seat and retainer.

11. In a carbureter, an air supply conduit, a conduit for carbureted air lying above the aforesaid conduit, parallel transverse manifolds connected to the front ends of said conduits and each communicating with one of said conduits, a series of tubes arranged between and connecting said conduits together, a fuel supply nozzle projecting into the lower end of each tube, and means for delivering fuel to said nozzles.

12. In a carbureter, an air supply conduit, a conduit for carbureted air lying above the aforesaid conduit, parallel manifolds connected to the front ends of said conduits and extending transversely of the same, a series of tubes connecting said manifolds together, a nozzle arranged in the lower end of each of said tubes, a fuel manifold having connections with said nozzles, and means for delivering fuel into the fuel manifold.

13. In a carbureter, two straight manifolds arranged parallel with each other and one above the other, a series of transparent tubes lying between the manifolds in a row extending lengthwise of the manifolds for connecting the manifolds together, an air-supplying conduit lying behind and connected to the lower manifold, a conduit for carbureted air lying behind and connected to the upper manifold, a nozzle arranged in the lower end of each of said transparent

tubes, and means for supplying fuel to said nozzles.

14. In a carbureter, two straight manifolds arranged parallel with each other and one above the other, a series of transparent tubes lying between the manifolds in a row extending lengthwise of the manifolds for connecting the manifolds together, an air-supplying conduit lying behind and connected to the lower manifold, a conduit for carbureted air lying behind and connected to the upper manifold, a nozzle arranged in the lower end of each of said transparent tubes, and means lying behind said manifolds for supplying fuel to said nozzles.

15. In a carbureter, a carbureting device including a series of transparent tubes arranged side by side in a row, means behind said carbureting device for supplying air and a carbureting element to said tubes, and a conduit for carbureted air lying wholly behind and extending rearwardly away from said carbureting device.

16. In a carbureter, two straight parallel manifolds arranged one above the other, a series of transparent tubes arranged between and connecting said manifolds together, said tubes being arranged in a row extending throughout the length of the manifolds, nozzles projecting into the lower ends of said tubes, and automatic valves arranged in the upper ends of a portion only of said tubes, said valves being so constructed and arranged that they will open in succession under an increasing suction.

In testimony whereof, I sign this specification in the presence of two witnesses.

LEVI S. GARDNER.
